WRAP-STRETCH MEANS

George E. Larsen, Hawthorne, Calif., assignor to Northrop Aircraft, Inc., Hawthorne, Calif., a corporation of California

Application July 3, 1950, Serial No. 171,852

3 Claims. (Cl. 153—48)

The present invention relates to wrap-stretch forming of thin sheets and more particularly to a means and method of wrap-stretching thin sheets to form channelled parts that are closed to relatively small dimensions. The invention is particularly adapted for the production of thin leading edge skins for aircraft wing and tail surfaces, or the like, and for curved edges such as might be used around jet engine inlets on airplanes.

It is an object of the present invention to provide a means and method of forming thin sheets into parts having U-shaped sections, particularly when the open ends of the parts are relatively closely spaced.

It is another object of the invention to provide a means and method of forming deep U-shaped channels from sheet metal in which the lips of the channels are simultaneously formed to a desired curve.

It is a further object of the present invention to provide a means and method of forming U-shaped channels from sheet metal when the extent of the channel is curved.

It is still a further object of the invention to provide a means and method of forming U-shaped channels from sheet metal by which the channel metal is progressively stretch hardened.

And it is still another object of the invention to provide a means and method of forming U-shaped channels of sheet metal that are stretch hardened only after being formed to shape.

Briefly as to method, the invention comprises gripping a metal sheet by opposite edges thereof so that these edges can freely move toward each other over controlled arcs. The nose of a die of the desired contour is then applied intermediate the gripped edges and moved toward the sheet to wrap the sheet around the die, the gripped edges moving freely toward the die under the urge of the die until the sheet is wrapped around and conforms to the die.

Die movement is then continued, first stretching the metal areas having the least die friction, this stretching progressing toward areas having greatest die friction. Die movement is continued until all of the metal is stretched and set to desired shape. U-shaped channels of any useful depth can be made by this process with the open ends of the channels spaced as little as one-half inch, if desired.

Briefly as to apparatus, means are provided to grip opposite edges of a metal sheet, these gripping means being mounted on spaced hinged arms to swing freely toward each other over predetermined arcs. A ram, such as appears on a hydraulic brake, is provided with an end die of the desired shape, and means are provided to force the die against the sheet intermediate the gripping means to wrap the sheet around the die. After the sheet has been wrapped around the die, relative movement of the die and sheet is continued to stretch and set the metal of the wrapped and formed sheet. If it is desired that the areas of the sheet adjacent the gripping means be contoured in a reverse curve, secondary dies can be provided on the arms adjacent the gripping means.

Other objects, advantages and features of the present invention will be found by reference to the ensuing description of the drawings in which:

Figure 1 is a perspective view, somewhat diagrammatic, of one preferred form of apparatus for forming leading edge skins for use in airplanes, in accordance with the present invention.

Figure 1a is a perspective view on a small scale, showing a power brake equipped with the apparatus of Figure 1.

2

Figures 2 and 3 are cross sectional diagrammatic views of the device of Figure 1 showing sheet suspension prior to wrap, and final wrap, respectively.

Figures 4 and 5 are schematic cross sectional views showing sheet position before and after wrap, respectively, of a device modified to contour the lips of the formed channel.

Figure 6 is a cross sectional view of a sheet gripping means used on the device of Figure 1 taken as indicated by line 6—6 in Figure 1.

Figure 7 is a cross sectional view of the sheet gripping device taken as indicated by the line 7—7 in Figure 1.

Figure 8 is a schematic perspective view showing how a curved channel can be formed in accordance with the present invention.

Figure 9 is a diagrammatic perspective view showing the base of the forming machine for another embodiment wherein tapered channels are formed.

Figure 10 is a diagrammatic plan view of the apparatus in Figure 9, on a smaller scale, showing convergence of the hinge lines of the work holders.

Referring first to Figures 1 and 1a, a straight ram 1, such as may be found on a 600 ton hydraulic brake 2 for example, is provided with a primary die 3 held thereon by an extended key 4. Die 3 is externally contoured, for example, to form a leading edge for an airplane wing, and is made as long horizontally as desired, within the capacity of the brake. As shown in Figure 3, die 3 has a rounded nose 3a, and curved faces that curve smoothly 30 rearwardly from the nose and terminate at a heel portion 3b near the base of the die in such manner that vertical transverse sections through the die show that the rearward terminal portions of the side faces extend in generally parallel direction. As shown in the drawings, the die is 35 of considerably greater depth than thickness.

The bed plate 6 of the brake is provided with two spaced parallel and aligned rows of jaw bearings 7 passing around hinge pins 8 at the lower ends of two rigid jaw arms 9, both jaw arms being in this case alike. Hence, the axes of the pins 8 are in a common plane perpendicular to the path of movement of the die 3. The axes of the pins 8 are also symmetrically arranged with respect to the die 3 and are spaced apart along their length at distances at least as large as the corresponding major thicknesses of the die 3.

Each jaw arm 9 comprises a plate 10 as long or longer, for example, than primary die 3, reinforced by side ribs 11. Outwardly each arm 9 terminates in a gripper bar 12, these bars being parallel to the extent of the ram 1 and primary die 3. Jaw arms 9 are at all times respectively free to swing without restraint about the axes of their hinge pins 8 between generally horizontal and vertical positions.

Each gripper bar 12 is provided with a sheet gripping assembly best shown in Figures 6 and 7. Here, the gripper bar 12 is provided with a longitudinal groove 15 having converging side inserts 16 in which are inserted a pair of longitudinal wedges 17 running the full length of the bar 12 and shaped to slide in groove 15 from an extended position where hardened and serrated facing surfaces 18 of the wedges 17 are in contact, to a retracted position where the inner surfaces 18 are spaced. A plurality of longitudinal rollers 20 are inserted between each wedge 17 and the side inserts 16, on which it moves, 65 to facilitate such movement. In this embodiment, the surfaces 18 extend generally parallel to their plates 10.

As shown in Figure 7, at intervals along the extent of the gripper assemblies, air cylinders 21 are provided having pistons 22 bearing against the inner surfaces of wedges 17 to force the wedges outwardly in groove 15 to close. The wedges are spread, or opened, by springs 23 operating through tension rods 24 engaging the inner portions of wedges 17, as shown in Figure 6. During movement of the wedges, rollers 20 are maintained in place by spring operated push rods 25 bearing against the top roller of each group thereof. It is convenient to place air cylinders 21, opening springs 23 and push rods 25 in groups spaced uniformly along gripper bars 12, as indicated in Figure 1. All of the air cylinders 21 are provided with flexible air hoses 27, and are connected to

an air pressure source through a control valve (not shown) for simultaneous operation on each jaw arm 9.

When leading edge channels of U-shaped sections are to be formed, when the lips or legs of the U channel are not to be specially formed, the wedges are positioned in the gripper bars so that when the arms 9 are rotated apart, as shown in Figure 2, they will receive, without substantial bending, the opposite edges of a metal sheet 30 to be wrap-stretched.

With the wedges 17 closed on the sheet edges by air pressure, the sheet will be suspended, with a slight belly therein, in space between the two arms, below ram 1 with its attached primary die 3. The amount of belly will of course depend on the width of the sheet, the ram stroke length, and the amount of final stretch desired. Normally, the sheet will be wide enough to spread the arm 9 so that the planes containing the latter extend at a substantially obtuse angle.

With the sheet suspended, as shown in Figure 2, the ram 1 is lowered or advanced from its retracted position and the nose 3a of the primary die 3 will contact the sheet. Further lowering or advancing of the die 3 will force the sheet downwardly, thereby swinging the arms 9 toward the primary die 3 until the sheet is fully wrapped around the primary die as shown in Figure 3. During this wrap, the arms are not driven in any way, except by the pull of the sheet, nor is the material stretched. Full wrap is obtained before stretching begins.

After the full wrap has been attained at a first advanced position of the die, the ram with its attached primary die is moved downwardly an additional distance to a second advanced position to stretch the metal. This stretching will begin in the metal between the wedges 17 and the heel 3b of the primary die 3. As this metal stretches, it hardens and resists further stretching, the unstretched metal beyond then stretching against the frictional resistance of the primary die contact. In this manner the metal is progressively stretched until all of the original metal is stretched, even around the nose 3a of the primary die. After the entire formed channel has thus been stretched and hardened, the ram 1 is retracted, air pressure is cut off from cylinders 21, the wedges separate, and the formed part is removed.

When it is desired that the lips or edge areas of the channel be contoured, a modified structure as shown in Figures 4 and 5 is utilized. Here, the wedge cavities open toward each other, i. e. the gripping surfaces 18 are generally perpendicular to the plane of their corresponding arms 9 and secondary lip contouring dies 31 are positioned on arms 9 so that when the sheet 30 to be wrap-stretched is clamped between the wedges 17, with the sheet in a generally horizontal position, the edge areas of the sheet are draped across the secondary dies 31, as shown in Figure 4. The primary die 3, which in this case can be as narrow as desired, is then forced against the sheet as previously described. After the ram has been lowered to obtain a complete wrap over both primary and secondary dies, with the arms 9 moving freely toward the primary die and engaging the sheet between the latter and the secondary dies, due to primary die pressure on the sheet, as shown in Figure 5, additional downward movement of the ram causes the sheet material to stretch; this stretch starting at areas of least die friction and spreading progressively to areas of higher friction until the entire part has been stretched and hardened. The ram is then raised and the formed, hardened part is removed with the channel lips contoured and stretch hardened.

Deep channels, with the sides thereof spaced as little as one-half inch, can be formed in this manner if desired. Channels tapered in thickness along their extent can readily be formed by proper lengthwise taper of primary die 3. In this case a corresponding convergence of the hinge lines is preferred. The latter embodiment is shown in Figures 9 and 10 (die and ram omitted), wherein the hinge pins 8, and therefore the plates 10, converge at an angle X, and the U-shaped channel 30a formed from the metal sheet tapers in thickness from a dimension A at one end to a lesser dimension B at the other end. For this embodiment, the metal sheet to be inserted into the gripper assemblies has a trapezoidal shape.

Curved channels can also be readily formed, as shown in Figure 8, and, if desired, the lips of the channels can be asymmetrical in shape and contour. In Figure 8, the secondary dies 31 are made to have different curvatures and different extents away from the channel sides. In

plan-form, one of the dies 31 has a convex curvature as indicated by numeral 32 and the other die 31 has a concave curvature as indicated by numeral 33. Die 3 has sides curved along their length to fit between secondary dies 31, and, if desired, the primary die 3 may have an asymmetrical nose 3a. The forming procedure is the same as has been previously described, the part being first wrapped and then stretched, although in this instance a complete wrap over the secondary dies cannot always be made until after stretching has started due to the differing extent of the secondary dies from the wedges 17.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is, therefore, claimed in any of its forms or modifications within the legitimate and valid scope of the appended claims.

What is claimed is:

1. Apparatus for forming and wrap-stretching a flat sheet metal blank into a thin structural channel of generally U-shaped section having considerably greater depth than width, comprising: an elongated thin primary forming die substantially U-shaped in cross-section and of considerably greater depth than thickness, said die having a curved nose and side faces that curve smoothly rearwardly from said nose in such manner that transverse sections through the die show the rearward terminal portions of said faces extending in generally parallel directions; means for moving said die rectilinearly from a retracted to advanced first and second positions; a bed plate; a pair of rigid jaw arms mounted for unrestrained pivotal movement about the corresponding axes of a pair of stationary hinges secured to said plate; said axes being disposed in a common plane perpendicular to the path of movement of said die and positioned in spaced opposition to said die nose in said second position of said die, and said axes being generally symmetrically arranged with respect to said die and spaced apart along their length at distances at least as large as the corresponding major thicknesses of said die; and means mounted on said jaw arms remote from said hinge axes for gripping opposite edges of a flat sheet metal blank of sufficient dimension between its said edges to spread said jaw arms apart so that the planes containing said arms extend at a substantially obtuse included angle therebetween, said die in advancing from said retracted position to said first position being effective to contact the blank intermediate its said edges and thus pivotally move said arms toward each other to wrap the blank about said die nose and side faces and conform the blank to the configuration of said die, and said die in advancing from said first to said second position being effective to stretch said blank beyond its elastic limit.

2. The structure defined in claim 1, in which the effective blank-engaging surfaces of the gripping means are disposed generally parallel to the jaw arms.

3. The structure defined in claim 1, in which the effective blank-engaging surfaces of the gripping means are disposed generally perpendicular to the jaw arms and include a secondary die on at least one jaw arm adjacent the gripping means thereon and opposed to the other jaw arm, said secondary die being adapted to engage the face of the blank opposite that engaged by the primary die, with the blank being engaged between said primary and secondary dies in the first position of the former.
